ELECTROMAGNETIC RELAY

Original Filed August 19, 1921

Fig. 3

UNITED STATES PATENT OFFICE.

MARTIN L. NELSON, OF PARK RIDGE, ILLINOIS, ASSIGNOR, BY MESNE ASSIGNMENTS, TO AUTOMATIC ELECTRIC INC., OF CHICAGO, ILLINOIS, A CORPORATION OF DELAWARE.

ELECTROMAGNETIC RELAY.

Application filed August 19, 1921, Serial No. 493,630. Renewed November 2, 1925.

The present invention relates in general to electromagnetic relays and has for its object the provision of a new and improved marginal or two-step relay.

5 Relays of this character have been constructed before and generally have two windings of different magnetizing strengths, or a single winding the magnetizing strength of which can be altered by the introduction 10 of a resistance in series with it or by other appropriate means, the object in any case being to secure either partial or a complete operation of the relay as desired. While these prior arrangements accomplished the 15 desired results it will be appreciated that the operation of a relay so constructed was not as positive as could be desired.

The marginal relay of the present invention was designed with a view to producing 20 a relay whose operation is absolutely positive.

Another object of the invention is to apply this two-step relay to a rotary lineswitch circuit whereby the mechanical interlocking 25 device which has hitherto been necessary between the armatures of the line and switching relays is eliminated and the operation of the circuit improved.

The improved two-step relay in its preferred form is illustrated in the drawing 30 which will now be referred to for a more detailed description of its construction and operation.

Referring now to the drawing, Figs. 2 35 and 3 show side and back views, respectively, of the improved relay. Fig. 1 shows the circuit of the improved rotary lineswitch for an individual subscriber's line in an automatic telephone system using the improved 40 two-step relay.

The operation and the construction of the improved marginal relay will now be described in detail with reference to Figs. 2 and 3. Like parts in the various figures 45 have been given the same reference characters in order to facilitate the explanation. The relay proper is made up of two coils 16 and 17 wound upon the cores 61 and 62, which are attached by means of a single 50 screw 63 to the iron heel piece 41. The heel piece 41 is made so that when the coils 16 and 17 are mounted in place the cores 61 and 62 are the same height but the top of the

heel piece 41 is slightly shorter. The armature 47 is mounted on the bracket 65 by 55 means of the flexible spring 50 which is fastened to the bracket at one end by means of the screws 45 and 46 and to the armature at the other end. The spring 50 is preferably made of nonmagnetic material. The bracket 65, upon which the armature 47 is mounted, is attached in position on the heel piece 41 by means of the screws 48 and 49. The armature 47 is adapted through the medium of the levers 42 and 43 to operate the springs 65 21, 22, etc. When completely assembled the armature 47 is closer to the core 62 than it is to the core 61, as it is pivoted by means of the spring 50 on the bracket 65, which is mounted on the heel piece 41 slightly below 70 the cores 61 and 62. It will be noted that the bracket 65, carrying the armature 47, is mounted on the heel piece 41 by means of the screws 48 and 49 which fit in longitudinally shaped slots in the bracket 65. This 75 construction allows the armature to be very easily adjusted by loosening the screws 48 and 49 and shifting the bracket, without, however, varying the air gap between the armature and the bracket. The movement 80 of the armature is limited by means of the back stop 66 which limits the backward movement of the lever 42 and hence the armature 47. There is a similar back stop for the lever 43 which is not shown in the drawing. 85 These backstops are mounted in position by the same screws which hold the relay springs in place.

In order to describe the operation of the improved two-step relay it will be assumed 90 that the coil 17 is energized. When this occurs magnetic flux will be set up in a circuit which includes the core 62 of the coil 17, the heel piece 41, bracket 65, and armature 47. The armature will be attracted against 95 the core 62. A certain amount of flux will be set up in the core 61 of the coil 16, however, this flux will have no appreciable effect on the armature 47 as the core 61 is practically short circuited by the heel piece 41 and 100 bracket 65. Most of the flux will therefore flow through the heel piece and the armature 47 will be attracted until it engages the core 62 of the coil 17 and will not engage the core 61 of the coil 16 because, as was before 105 mentioned, the armature 47, on account of

the manner in which it is mounted, is closer to the core 62 than it is to the core 61. When the armature 47 is in this position only certain of the springs are operated, that is, the 5 spring 20 breaks away from its resting contact but does not engage its working contact, the spring 23 operates in a similar manner. The springs 21 and 22 are not operated at this time. When the winding 16 is energized, which may take place either when the 10 coil 17 is energized or deenergized, as this does not affect the operation, except that if the coil 17 is energized the current flow through the coil 16 must be in the opposite 15 direction to the current flow through the coil 17, armature 47 is fully attracted and changes its fulcrum on the spring 50 from a point close to the heel piece 41 to the point where it engages the core 62. By this operation 20 springs 20, 22 and 23 engage their working contacts, while spring 21 breaks away from its resting contact. The magnetic flux is set up in a circuit which includes the core 61, the core 62, and the armature 47, a certain 25 amount being shunted by the heel piece 41.

From the above it will become apparent that if the coil 17 is energized alone only the 30 springs 20 and 23 are operated, while if the coil 16 is energized all the springs will be operated. It will, of course, be understood that any desired adjustment can be made with the springs controlled by the armature 47 without departing in any way from the 35 spirit of the present invention.

It will now be in order to explain why the 40 spring 50 is made of non-magnetic material. It is some time desirable to energize the core 16 without deenergizing the coil 17. Under these 45 conditions it is necessary for the armature 47 to shift its fulcrum as described. Now if the spring 50 were of magnetic material the armature 47 would tend to stick to the heel piece 41 as there would be practically 50 no air gap between the armature 47 and the heel piece 41 and thus the armature would tend to be prevented from changing its fulcrum. By making the spring 50 of non-magnetic material this difficulty is not 55 encountered.

Having described the construction and operation of the improved two-step relay, the manner in which a rotary line switch, in which this two-step relay is used, operates 60 will now be described. For this purpose it will now be assumed that a calling subscriber whose line terminates at the exchange in the line switch C desires to initiate a call. The subscriber's substation has not been 65 shown in the drawing but it will be understood that this substation is of the usual automatic type, which, when the receiver is removed, places a bridge across the two line conductors 11 and 12 which includes the calling 70 device springs, transmitter and receiver.

Immediately upon this bridge being placed across the line conductors 11 and 12, a circuit is completed for the line relay 14 of the line switch C over the two line conductors in series. Relay 14, upon energizing, at its armature 25 completes a circuit which includes the two coils 16 and 17 of the switching relay 15 and the motor magnet 18 in series, and at its armature 26 connects the test wiper 28 to the above circuit at a point midway between the switching relay and the 75 said motor magnet. The operation of the line switch C now depends upon whether its switch wipers 27-29, inclusive, are associated with an idle trunk line or not. If the 80 associated trunk line is busy, there will be a ground potential present upon the test contact engaged by the test wiper 28, switching relay 15 is short circuited, and the motor magnet 18 being supplied with direct ground 85 by way of the said test wiper will operate as a buzzer to advance the switch wipers step by step in search of an idle trunk line. However, it will be assumed in the present case, when the receiver is removed at the calling 90 substation, that the switch wipers of the line switch C are associated with an idle trunk line and it will be assumed further that this trunk line is the one shown in the drawing terminating in bank contacts 30-32, inclusive. Under these conditions, immediately 95 following the energization of the line relay 14, the switching relay 15 is energized in series with the motor magnet 18. Relay 15, upon operating, at its armature 22 places 100 ground upon the test contact 31, and at its armatures 20 and 23 disconnects the line conductors 11 and 12 of the calling substation from the windings of the line relay 14 and from ground, respectively, and extends by 105 way of wipers 27 and 29, bank contacts 30 and 32, over the line conductors of the selected trunk line to the upper and lower windings of the line relay of the automatic switch associated with the seized trunk line. 110

Immediately upon the line conductors being extended to the line relay of the selected switch, this relay is energized over the calling line loop and completes the circuit of its associated slow acting release relay. The 115 latter relay, upon energizing, prepares the operating circuits of the selected switch and places ground upon the release trunk conductor of the associated trunk line thereby completing a holding circuit for the line switch C. This circuit extends from ground on test contact 31, test wiper 28, armature 22 and its front contact, through the windings 16 and 17 of the switching relay 15 in series, and thence through the winding of 120 the motor magnet 18 to battery. It will be understood that the slow acting line relay 14 maintains its armature attracted until 125 this holding circuit is completed. A branch of this holding circuit also extends by way 120

of the private normal conductor 30 to multiply connected test contacts in the banks of the connector switches which have access to the line of the calling substation whereby the said line is protected from intrusion in the usual manner.

The above is the normal operation of the line switch C when its associated line is calling. When its associated line is called, 10 upon the connector extending the connection to the line, ground is placed upon the private normal conductor 30 which extends by way of armature 25 and its back contact, back contact and armature 21, through the 15 winding 17 of the switching relay 15 and thence through the winding of the motor magnet 18 to battery. It will be remembered that the coil 17 is only adapted to operate the armatures 20 and 23 of the relay 20 15 out of engagement with their resting contacts but it does not cause them to engage their working contacts. The other armatures of the relay 15 are not operated at this time due to the novel construction of the 25 improved two-step relay. Consequently, by this operation the line of the called substation is disconnected from its normal battery and ground connections in the line switch C, but is not connected through to the wipers 30 of the switch.

From the above it will be seen that this improved relay construction obviates the necessity of providing a mechanical locking device between the armatures of the line relay 14 and the switching relay 15 in the line switch C. It will, of course, be apparent that this relay is not limited in its application to a rotary lineswitch but may be used wherever a relay having a two-step operation is desired.

The features of the invention having been fully described and ascertained what is considered to be new and desired to have protected by Letters Patent will be pointed out 45 in the appended claims.

What I claim as my invention is:

1. In an electromagnetic relay having a pair of coils wound upon different cores attached to a heel piece, an armature adjustably mounted on said heel piece, said armature being adapted to move on two different fulcrums, means for energizing one of said coils to cause said armature to move about the end of said heel piece as one fulcrum, 55 and means for energizing the other of said coils to cause said armature to move about the end of the core of the coil first energized as the other fulcrum.

2. In an electromagnetic relay having a pair of coils wound upon different cores, an armature for said relay adapted to move about two different fulcrums, one of said fulcrums being adjustable and the other fixed, the fixed fulcrum being at the end of 60 the first one of said cores, means for energiz-

ing the coil wound on said first core to cause said armature to move on the adjustable fulcrum, and means for energizing the other of said coils to cause said armature to move in the same direction on the fixed fulcrum. 70

3. In an electromagnetic relay, two separate magnet cores, an armature movable about two different fulcrums by said two cores, respectively, a heel piece and a bracket for suitably supporting said armature adjacent said cores, and means for adjusting said bracket on said heel piece to regulate the normal position of said armature. 75

4. In an electromagnetic relay, a core and a heel piece mounted substantially parallel 80 to one another, an extension bracket adjustably secured to said heel piece, an armature attached to said bracket and adapted to be moved about a portion of the bracket as a fulcrum when said core is magnetized, and a second core parallel to said first core and 85 adapted when magnetized to move said armature on the extremity of said first core as a fulcrum.

5. In an electromagnetic relay, two magnet cores and a heel piece disposed in parallel planes and magnetically connected at one end, the second core lying between the first core and the heel piece, an armature having two fulcrums, one on the free end of 90 said heel piece and the other on the free end of said second core, said armature responsive to magnetization of said second core to move about the first fulcrum into engagement with the second fulcrum, and responsive to magnetization of said first core to move about 95 said second fulcrum, and means for adjusting the initial position of the said first fulcrum. 100

6. In an electromagnetic relay, two magnet cores and a heel piece disposed in parallel planes and magnetically connected at one end, the second core lying between the first core and the heel piece, an armature fulcrumed on the free end of said heel piece 110 at a point below the plane of the free ends of said cores, said armature moving on said fulcrum into engagement with the said second core responsive to the magnetization thereof and moving on the end of said second core as a fulcrum responsive to the magnetization of said first core, and means for adjusting the distance between said first fulcrum and the plane of the free ends of said cores. 115

7. In an electromagnetic relay, a flat armature having a support at one end thereof, a core adjacent the center of said armature and adapted to attract the said armature when magnetized, a second core adjacent the other end of said armature and parallel to said first core but shorter, so that the said armature will not engage the second core when the armature is attracted by the first core, and means securing the armature to 125 130

said support such that when the said second core is magnetized the armature will turn on the end of the first core as a fulcrum.

8. In an electromagnetic relay, two magnet cores and a heel piece disposed in parallel planes, and magnetically connected at one end, the said heel piece being of such a length that it is not intersected by the plane determined by the free ends of said cores, 10 and an armature adjustably supported on the free end of said heel piece and operable either to close the gap between the heel piece and one core or to close the gap between the two cores.
13. 9. In a two step relay, an armature, an adjustable support for said armature, a magnet core for operating said armature a definite distance on said support as a fulcrum, contact springs actuated by said armature, a second magnet core for causing said armature to resume its movement for an additional distance, means attaching said

armature to the said support such that the armature is permitted to shift its fulcrum at the beginning of the second stage of its movement, and other contact springs actuated by said armature in the second stage of its movement.

10. In an electromagnetic relay, two cores and a heel piece disposed in parallel planes, a flat armature extending across the ends of said cores and the end of said heel piece, a thin spring of non-magnetic material disposed between said armature and the ends of said cores and heel piece, an adjustable bracket for attaching one end of said spring to the heel piece, and means for attaching the other end of said spring to the armature at a point between the ends of said cores.

In witness whereof, I hereunto subscribe my name this 12th day of August, A. D., 1921.

MARTIN L. NELSON.
